No. 821,257.

PATENTED MAY 22, 1906.

W. A. RAGSDALE.

SYSTEM OF DELINTING COTTON SEED AND RECOVERING LINT.

APPLICATION FILED MAR. 7, 1906.

UNITED STATES PATENT OFFICE.

WILLIAM ADRON RAGSDALE, OF WASHINGTON, DISTRICT OF COLUMBIA,
ASSIGNOR TO INTERNATIONAL COTTON SEED DELINTING COMPANY,
OF WASHINGTON, DISTRICT OF COLUMBIA, A CORPORATION OF MAINE.

SYSTEM OF DELINTING COTTON-SEED AND RECOVERING LINT.

No. 821,257.

Specification of Letters Patent.

Patented May 22, 1906.

Application filed March 7, 1906. Serial No. 304,775.

To all whom it may concern:

Be it known that I, WILLIAM ADRON RAGSDALE, a citizen of the United States, residing at Washington, District of Columbia, have 5 invented certain new and useful Improvements in Systems of Delinting Cotton-Seed and Recovering Lint, of which the following is a specification.

This invention relates to the art of delinting cotton-seed, and has particularly in view an improved system of instrumentalities so arranged and operated as to provide a practical and valuable method of handling ginned cotton-seed, whereby such seed will be thoroughly delinted or cleaned of the adhering lint and the latter will be recovered in its entirety and at the same time graded into separate and distinct commercial by-products.

In the first place, in the practical operation 20 of cotton-seed-oil mills the preparation of the seed for the mills is a step in the process which is of the utmost importance, and the present invention contemplates a system of machinery and method of handling the ginned seed, 25 whereby the latter will be thoroughly delinted and placed in the best possible condition for the oil-mill. In the second place, another feature of importance is the disposition of the lint removed from the ginned seed. In this 30 connection the present invention aims to perfect a system wherein there may be effectively employed the plan of arranging a linting mechanism between the ginning and delinting mechanisms and utilizing a separator for 35 short fiber and fiber ends in connection with a delinting mechanism comprising means for preparing the short fiber for an effective treatment by the separator.

In the above connection it is the purpose of 40 the present invention not only to recover from the delinting process the long lint as a commercial commodity, but also to recover as a second by-product and commercial commodity the aforesaid short fiber and lint ends 45 which have a well-recognized market value.

Hence the improved system contemplated by the present invention involves, first, the thought of linting and delinting cotton-seed, and, second, the important feature of recovering 50 and grading the long fiber and short fiber, whereby the system produces three separate and distinct marketable products—to wit, clean or delinted unhulled cotton-seed ready

for the oil-mills and separate grades of lint, one of which is a high-grade product and the other of which is a low-grade product. This high-grade product of lint is useful in spinning-mills for various purposes, while the low-grade product can be utilized in the manufacture of paper, battings, felt, and other 6c articles.

The essential features of the system involved in carrying out the objects above indicated are necessarily susceptible to a wide range of modification in the specific construction of the machines making up that system without departing from the scope of the invention, but a preferred and practical embodiment of the system or process is illustrated in the drawing, in which the figure is 70 a general diagrammatic sectional view of a plant embodying the improved system forming the subject-matter of this application.

In carrying out the present system a distinctive feature thereof, as above explained, 75 resides in the provision of instrumentalities which separately recover and distribute the long fiber and the short fiber, which is removed from the seed as it comes from the gin. This is accomplished through the employment of what may be termed a "short-fiber" or "delinter" mechanism and a "long-fiber" or "linter" mechanism, co-operating with each other in the linting, delinting, and separating operations.

Any approved construction of short-fiber mechanism and long-fiber mechanism may be employed in carrying out the system claimed herein so long as these mechanisms perform in their proper relation the functions contemplated by the present invention. However, there is shown in the figure of the drawing a construction and arrangement of mechanisms and parts which by actual experiment have been found to successfully and 95 thoroughly accomplish the object of the invention—viz., to deliver from the plant in condition for the market three separate by-products—to wit, thoroughly delinted or cleaned unhulled cotton-seed and cotton lint in two 100 grades, one being a high-grade product of comparatively long fiber, the other being a low-grade product of short fiber ends.

Referring now to the illustrative drawing, suggesting one of the preferable ways of operating the plant or system, the number 1

designates in its entirety the delinter or short-fiber mechanism, which mechanism is so constructed and arranged as to provide for thoroughly removing the very short fiber from the hull of the seed and to deliver the latter in a thoroughly cleaned condition ready for use in the oil-mills. While various types of the short-fiber mechanism 1 might be utilized as one of the instrumentalities in this system, a construction which has been demonstrated as very practical for this purpose is of the general type embodied in my companion applications filed October 18, 1905, Serial No. 283,357; filed 15 October 18, 1905, Serial No. 283,358; filed November 17, 1905, Serial No. 287,812. This type of machine embodies in its general organization an outer case 2, an interior cylindrical scouring-shell 3, arranged within the case in spaced relation to its wall, and a rotary agitator 4, arranged for rotation within the scouring-shell 3 and coöperating therewith. The outer case constitutes a suction-chamber which completely envelops the scouring-shell 3, and said case is formed with a suction-hood portion 5, to which is connected one end of a suction discharge-pipe 6, leading to the inlet of an exhaust or suction fan F, the latter constituting one of the essential instrumentalities or machines forming a part of the system or plant.

The scouring-shell 3 of the short-fiber mechanism is of a sectional construction and essentially consists of a series of parallel abrasive rings 7, arranged side by side in regular spaced relation to leave therebetween intervening annular discharge-slits 8, preferably of outwardly-flaring form and in communication with the working space within 20 the shell and also in communication with the suction-chamber surrounding such shell. This construction provides an ample and free discharge entirely about the scouring-shell for the dust and trash, and particularly 25 for the short fiber and lint ends removed from the hull of the seed. Also the short-fiber mechanism illustrated preferably embodies a hollow perforate air-drum 9 in communication with the outer air and also carrying 30 a plurality of pressure-blades 10, coöperating with the abrasive surface of the ring 7 and having continuously saw-toothed edges. This construction provides for freely admitting an unlimited and full supply of air into 35 the scouring-shell from the center outward, thus insuring a complete discharge of the short fiber and lint ends into the case and thence into the suction discharge-pipe 6.

The short-fiber mechanism 1 is provided 40 at one end of its case with a seed-inlet 11 and at the opposite end with a seed-outlet 12, the latter being in communication with a conveyer 13, which receives the delinted or cleaned seed and delivers the same to a seed 45 receptacle or bin 14.

The long-fiber mechanism or linter (designated in its entirety by the number 15) is arranged to deliver seed, denuded of its long fiber, to the seed-inlet 11 of the short-fiber mechanism. This long-fiber mechanism acts upon the seed in the condition in which it comes from the gin G, (see drawing,) and said mechanism preferably consists of a saw-cylinder 16, a discharging-brush 17, and a condenser 18. The saw-cylinder 16 comprises a cylinder or gaing of separating-saws spaced in much closer relation than the saws of a gin, and, acting upon the seed as it comes from the gin, said saws serve to remove the long fiber or lint and permit the seed, with the closely-adhering short lint or fuzz, to be delivered by conveying means 19 to the inlet of the short-fiber mechanism. The brush 17 operates against the saws at one side of the saw-cylinder, and the fan action of said brush 20 serves to sweep the long lint from the saws and blow the same through the lint-discharging flue 19^a onto the condenser 18, alongside of which is arranged a baling-core 20, coöperating with the condenser 18 in the manner 25 common to condensing apparatus and serving to collect in a roll the long lint which constitutes the high-grade by-product of the system claimed herein.

The action of the exhaust-fan F serves to 30 draw the short lint from the short-fiber mechanism and forces the same through a blast-pipe 21 into the upper receiving end of a separating device 22, specially designed for the collection of all of the short fiber and lint 35 ends. The separating device 22 consists of an upright cylindrical body having a cylindrical separating-drum 23 at its upper end and a downwardly-tapering delivery-cone 24. The inlet 25 of the drum 23 connects with the blast-pipe 21 and is tangentially disposed, while the air-outlet 26 for said drum is pendant centrally therein and forms a center guard about which the air and cotton swirls. This swirling action in the drum 23 throws 40 the short fiber out to the wall of the drum 23 and outside of the suction or blast of the air. This permits the air to rush inward to the outlet 26, while the freed lint will fall by gravity 45 through the delivery-cone 24 onto the floor or into the receptacle provided therefor. The short fiber or lint thus recovered constitutes the second grade of lint which heretofore has 50 constituted a waste product of delinting systems.

In further explanation of the relation of this system to the prior art it is well known that heretofore cotton-seed-delinting machines have most generally been designed to operate directly on the seed in the condition in which it comes from the saw-gins. Under such conditions the delinting-machines are required to operate upon cotton-seed having thereon not only the closely-adhering fuzz or short fiber, but also a long fiber approximat-

ing from three to five eighths of an inch in length. A fiber of this length in any construction of delinting mechanism is a serious obstacle to a proper delinting action. This 5 long fiber in the delinting operation invariably produces a roping, balling, and bunching of fiber, which if not disposed of by some mechanical means invariably clogs the delinting machine after a short running, causing a heating 10 of the seed and an imperfect delinting action. Consequently it has been the constant aim of cotton-seed experts to provide delinting-machines with auxiliary devices to dispose of the, lint ropes, balls, and bunches 15 caused by the long fiber carried by the ginned seed into the delinting mechanism. Many mechanical devices have been evolved in delinting mechanisms for overcoming these difficulties; but the present invention provides 20 a system wherein the linting action of a linter is utilized as the step immediately preceding the delinting action, whereby the long fiber referred to is eliminated from the delinting operation and is recovered as a second-grade 25 product entirely aside and independent from the fiber product recovered from the delinting action. This in itself is an important feature commercially, for the reason that in such cotton-seed processes where the delinting 30 mechanism operates directly upon ginned seed the two grades of fiber are recovered as one product, the long fiber being reduced to the low grade (commercially) of the short fiber. Also in carrying out the present invention 35 it has been found by experiment that a complete and proper recovery of the short-fiber product in condition for the market is

made possible by employing a preliminary 40 combing or disintegrating of the short fiber and trash before being blown to the separator. This is effected in the present invention through a feature of the delinter—viz., that of the toothed blades 10, which provide for 45 combing the short fiber and trash as a separating step preliminary to the main separating step therefor.

I claim—

A system of treating cotton seed and lint 50 consisting of the following instrumentalities: a ginning mechanism, a linting mechanism receiving the cotton-seed product from the ginning mechanism, and comprising means for removing from the seed a second-grade long fiber and eliminating such fiber from the succeeding delinting operation, a delinting mechanism receiving the linted seed from the linting mechanism and comprising means for moving from the seed the remaining short fiber thereon, said mechanism also having means for disintegrating the short fiber and 55 trash as a step preliminary to the main separating step therefor, a suction appliance for drawing the short fiber from the delinting mechanism, and a separator receiving the discharge from the suction appliance, and comprising means for collecting from the blast a 60 third-grade short fiber.

In testimony whereof I hereunto affix my signature in the presence of two witnesses.

WILLIAM ADRON RAGSDALE.
